UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

LOCK.

SPECIFICATION forming part of Letters Patent No. 373,107, dated November 15, 1887.

Application filed September 26, 1887. Serial No. 250,755. (No model.)

To all whom it may concern:

Be it known that I, WARREN H. TAYLOR, of Stamford, in the county of Fairfield and State of Connecticut, have invented a certain 5 new and useful Improvement in Locks, of which the following is a specification, reference being had to the accompanying drawings.

The object of my invention is to prevent the unscrewing of the set-screw ordinarily used to fix an escutcheon in place in a lock, and thus to prevent the escutcheon from being unscrewed and removed.

In ordinary locks the escutcheon is screwed 15 in place and a set-screw is set into a groove in the side of the escutcheon to fix it in the lock-case, so that it cannot be turned. When a door is unlocked, however, a mischievous person might slightly unscrew the set-screw, and 20 afterward, when the door is locked, might unscrew the escutcheon and get access to the interior of the lock, and thus unlock the door. To thwart this method of attacking ordinary door-locks, I provide means ordinarily sufficient 25 to prevent the set-screw from being turned when the lock is unlocked.

In the accompanying drawings, illustrating my invention, Figure 1 is a view of the lock with the cap-plate removed, so as to show the 30 interior of the lock, and Fig. 2 is an edge view of the lock partly broken away.

Referring to the letters upon the drawings, A indicates the lock-case, B a lock-bolt, and C a screw-threaded escutcheon set into the 35 case in the usual way.

D indicates a set-screw, and E a forked slide adapted to enter the grooves in two opposite escutcheons and hold them in place.

The devices thus far described are all old.

In connection with such devices my improvement consists in providing a thin face-plate, F, to be secured upon the ordinary face-plate, G, of a lock-case after the set-screw above described has been set in place to fasten the escutcheon. This, while not an absolute 45 prevention against the possibility of removing the escutcheon fastening set-screw, is yet a sufficient security in all ordinary cases, and is therefore an important practical improvement.

The additional thin face-plate or guard-plate may be secured in place by means of screws, as shown, or by means of rivets, or in any usual way, so that it would not ordinarily be practicable for a mischievous person to remove the plate and unscrew the set-screw without being observed. Where this guard-plate is used the set-screw should not be countersunk, as is usual, but should be made flush, so as to project and be observed if loosened, 55 and so that the guard-plate could not be put in place unless the set-screw were screwed in so as to hold the escutcheon.

What I claim to be new, and desire to secure by Letters Patent of the United States, is— 65

In a lock, the combination, with an escutcheon-securing set-screw, of a guard-plate covering the head of the set-screw and secured to the face-plate of the lock, substantially as set forth.

In testimony whereof I have hereunto subscribed my name.

WARREN H. TAYLOR.
